UNITED STATES PATENT OFFICE.

LOUIS J. KOSTER, OF WESTPHALIA, MICHIGAN.

ENGINE STARTER.

Application filed December 12, 1924. Serial No. 755,535.

To all whom it may concern:

Be it known that I, LOUIS J. KOSTER, a citizen of the United States, residing at Westphalia, in the county of Clinton and State of Michigan, have invented certain new and useful Improvements in an Engine Starter, of which the following is a specification.

This invention relates to engine starters and it consists in the novel features herein-after described and claimed.

An object of the invention is to provide a starter especially adapted to be used in conjunction with an internal combustion engine and which includes a starter shaft having an abutment member fixed at the end thereof and with a sleeve mounted for turning movement upon the shaft, a coil spring is connected at one end with the abutment member and at its other end with the sleeve, the sleeve is provided at its opposite end with cam edges and a collar is slidably mounted upon the sleeve and is provided with a gear wheel adapted to engage gear teeth provided upon the fly wheel of the engine. The said collar is further provided with a weight which disposes the center of gravity of the collar at one side of the axis of the shaft and whereby said collar will assume a normal position when the gear wheel thereof is disengaged from the fly wheel. The collar is provided at its opposite ends with cam edges adapted to engage the cam edges alternately of the sleeve, and friction means are provided for temporarily holding the collar in a fixed position with relation to the sleeve.

In the accompanying drawings:—

Figure 1 is a side elevational view of the engine starter showing the gear wheel thereof disengaged from the fly wheel of the engine.

Figure 2 is a longitudinal sectional view of the same.

Figure 3 is an end view of the engine starter.

Figure 4 is a side elevational view of the engine starter showing the gear wheel thereof in mesh with the fly wheel of the engine.

Figure 5 is a transverse sectional view of the starter cut on the line 5—5 of Figure 6.

Figure 6 is a side elevational view of the starter showing the relative positions of the

parts when the gear wheel of the starter is about to be engaged with the fly wheel. 55

Figure 7 is a perspective view of the sleeve used upon the starter.

As illustrated in the accompanying drawings, the engine starter comprises a shaft 1 which carries at one end the fixed abutment member 2. A sleeve is mounted upon the shaft 1 and is provided at its ends with cam edges 4 and 5 respectively. A coil spring 6 is connected at one end with the abutment member 2 and at its other end with the sleeve 3. The engine fly wheel is indicated at 7, and the said fly wheel is provided with gear teeth 8. A collar 9 is slidably mounted upon the sleeve 3 and is provided at its opposite ends with cam edges 10 and 11 respectively. A gear wheel 12 is mounted upon the intermediate portion of the collar 9 and the forward ends of the teeth of the gear wheel 12 are chamfered or beveled as at 13. A weight 14 is carried by the collar 9 and is disposed adjacent the gear wheel 12 and the center of gravity of the weight 14 is disposed at one side of the axis of the shaft 1 whereby the weight 14 will be disposed under the shaft 1 when the gear wheel 12 is disengaged from the teeth of the wheel 7 as shown in Figure 1 of the drawing. A spring finger 15 is mounted upon the sleeve 3 and is provided with a hump 16 adapted to engage in a dent provided upon the exterior surface of the sleeve 9 and whereby the parts are normally held in the position as shown in Figure 1 of the drawings.

Assuming that the parts are in a position as shown in Figure 1 and the shaft 1 is rotated, the abutment member 2 rotates with the shaft and the spring 6 causes the sleeve 3 to rotate with the shaft and whereby the hump 16 is disengaged from the dent in the collar 9 and the cam edge 5 moves along the cam edge 11 whereby the collar 9 is moved longitudinally of the sleeve and the teeth of the gear wheel 12 are moved into mesh with the teeth 8 of the wheel 7. At the same time the spring 6 is wound up tight around the abutment member 2 and the sleeve 3. As the wheel 12 is rotated, rotary movement is transmitted to the wheel 7 and the engine is started. When the wheel 7 picks up and begins to rotate faster than the wheel 12, 105 the cams 4 and 10 move relative to each

other so that the collar 9 is moved toward the abutment member 2 and the gear wheel 12 disengages the wheel 7 and the hump 16 engages in the dent in the collar 9 and the weight 14 falls to its normal position under the shaft 1.

Having thus described the invention, what I claim is:—

1. A starter comprising a shaft having an abutment member mounted thereon, a sleeve journaled upon the shaft, a coil spring connected at one end with the abutment member, and at its other end with the sleeve and disposed to be expanded by unwinding when the shaft is rotated, the sleeve being provided at its opposite ends with cam edges, a collar loosely mounted upon the sleeve and provided at its ends with cam edges adapted to engage the cam edges of the sleeve, gear teeth carried by the collar, spring means for normally holding the collar fixed with relation to the sleeve, abutments on the ends of the collar, and abutments on the sleeve at its

cam edges engageable with the abutments on the collar. 25

2. A starter comprising a shaft having an abutment member mounted thereon, a sleeve journaled upon the shaft, and provided at its opposite end portions with cam edges, a spring coiled about and connected to both the abutment member and the sleeve and disposed to expand by unwinding when the shaft is rotated, a collar loosely mounted upon the sleeve and provided at its opposite ends with cam edges, gear teeth mounted upon the collar, a weight mounted upon the collar and having its center of gravity disposed at one side of the axis of the shaft, a spring member mounted upon the sleeve and frictionally engaging the collar, abutments 35 on the ends of the collar, and abutments on the sleeve adjacent the cam edges thereof and engageable with the abutments on the collar. 40

In testimony whereof I affix my signature.
LOUIS J. KOSTER.
